UNITED STATES PATENT OFFICE.

LUTHER L. KNOX, OF BELLEVUE, PENNSYLVANIA, ASSIGNOR TO KATE A. KNOX, OF BELLEVUE, PENNSYLVANIA.

OPEN-HEARTH FURNACE.

Application filed October 14, 1920. Serial No. 416,792.

Figure 1 is a sectional plan view of an open hearth furnace embodying my invention.

Figure 2 is a section on the line II—II of Figure 1.

Figure 3 is a section on the line III—III of Figure 1.

Figure 4 is a section on the irregular line IV—IV of Figure 3.

Figure 5 is a transverse vertical section through one of the valve chambers, valve, and the adjacent ports.

Figure 6 is a sectional detail view showing a portion of one of the air ports.

Figure 7 is a plan view of one of the valve bodies.

Figure 8 is a vertical section through a part of one end portion of an open hearth furnace and illustrating a modification, and

Figures 9 and 10 are sections taken respectively on the lines IX—IX and X—X of Figure 8.

My invention has relation to certain new and useful improvements in open hearth furnaces, and is designed to provide a furnace of this character with a novel construction and arrangement of gas and air uptakes, waste-gas offtakes, slag pockets, regenerators and reversing valve mechanism for controlling the furnace and ports, whereby a more efficient operation of the furnace is made possible, and numerous other advantages are obtained, some of which are hereinafter pointed out.

The nature of my invention will be best understood by reference to the accompanying drawings in which I have shown preferred embodiments thereof and which will now be described, it being premised, however, that various changes can be made in the details of construction, arrangement and combination of the several parts, without departing from the spirit and scope of my invention as defined in the appended claims.

In these drawings, the numeral 2 designates the hearth or melting portion of the furnace and which is, in general, of any usual or suitable character and construction. 3 designates slag pockets, there being one of these pockets at each end of the furnace, each of said pockets being connected with the furnace through one or more offtake passages 4 and ports 5. In the construction shown there are three of the offtakes 4 at each end of the furnace (see Figure 1). 6

designate air supply ports, one at each end of the furnace, and which are supplied with air through regenerators or checkers in any usual or suitable manner. Each of these air ports 6 has an upwardly and backwardly extending portion 6^a (see Figure 6) which leads into a transversely extending portion 6^b, from which extend the air uptakes 6^c, terminating at their upper ends in the downwardly and forwardly directed inlet portions 6^d.

7 designates a gas port, one for each end of the furnace, and through which the gas is admitted through regenerators or checkers in the usual manner. Each of these ports 7 extends laterally, as shown at 7^a, (see Figure 1) across and below one end of the furnace to the opposite side of the furnace where it communicates with a transverse reversely extending portion 7^b. The gas uptakes 7^c lead upwardly from the port portions 7^b, (see Figure 2) and terminate in the forwardly and downwardly directed discharge portion 7^d. As will be seen from Figure 4, the inlet portion 6^d of the air inakes 6^c is separated from the discharge portion 7^d of the gas uptake by the arch 8, the air port extending over the said arch and downwardly at each side of the said discharge portion of the gas port. The arrangement of the discharge portion of the air and gas ports is such that the air and gas mix and combustion takes place before the air and gas enter the furnace proper. Both air and gas preferably are under pressure and this port arrangement gives what might be termed a "blow-torch" burner, the effect of which is to obtain an earlier and also a more complete combustion within the furnace chamber.

The offtake ports 5 are arranged above the arch 9 which separates them from the discharge portion of the air inlet ports, and also extend downwardly at the sides of the air and gas inlet ports, as shown at 9^a in Figure 4. By reason of this construction and arrangement, a large portion of the waste gases from the furnace chamber are not required to travel upwardly from the arch 9 in order to reach the offtakes 4, but can enter the offtakes through the side portions 9^a at a lower level. This not only gives a better outlet arrangement for the waste gases, but it very largely reduces the cutting and burning away of the roof walls of the

oftake ports 5. The arches 9 may be effectively protected by any suitable water-cooled arrangement, such as indicated at 9^b (see Figure 2).

5 Each of the slag pockets 3 has a port 10 which opens into a valve chamber 11 connected by a port 12 with one of the air inlet ports 6, as best shown in Figure 3. Each slag pocket is also connected by a port 13 10 with another valve chamber 14 which communicates by a port 15 with an adjacent gas inlet port 7. Each of the valve chambers 11 and 14 also leads to a regenerator or checker, one of which is shown at 15^a in Figure 4. 15 The regenerators or checkers may be of any usual or suitable character.

Each pair of ports 10 and 12 and 13 and 15 is arranged to be controlled by a reversible valve 16, or 17. In the construction 20 shown each of these valves consists of a hollow metal body to which is secured a hollow stem 18 which extends upwardly through the upper arched wall of the valve chamber and through a suitable water-seal 25 19, its upper end portion being connected to a suitable supply pipe 20 for the introduction of water or other cooling liquid. The valve stem is bent horizontally or offset between the vertical arm thereof which extends upwardly, as above described, and the 30 valve, so that when the stem is rotated about its vertical axis the valve will be moved from a position to seat over the port 10 to a position to seat over the port 12, or vice 35 versa. The action in this respect will be fully understood by reference to Figures 3 and 5. In order to permit the valve to be unseated at the beginning of its reversing movement and to be seated at the end of its 40 reversing movement, the valve and its stem are made capable of a vertical lift. This may be imparted by any suitable means, such as the power cylinder 21. The rotary movement of the valve may also be effected 45 by any suitable means such as the rack and pinion devices shown at 22 in Figures 1 and 4, the pinion members being made sufficiently broad faced to permit of the above described vertical movement of the valve 50 while remaining in gear with the actuating racks. These gears may be operated by power cylinders 24.

The operation is as follows:—In Figure 3 the valves are shown in the position they 55 occupy when gas and air are entering the right hand end of the furnace and the waste gases are coming out at the left hand end of the furnace. In this position it will be seen that each of the ports 12 and 15 is open 60 while each of the ports 10 and 13 is closed by the valves. The gas and air from the respective checkers or regenerators therefore pass into the valve chambers 11 and 14 and thence by the respective ports 6 and 7 to the 65 furnace. At the outgoing end of the fur-

nace, the ports 12 and 15 are closed by the valves, while the ports 10 and 13 are open. The waste gases, therefore, pass down the offtakes 4 and directly into the slag pocket 3. From this pocket they flow out in a 70 divided stream through the two ports 10 and 13, and thence to the respective regenerators at that end of the furnace.

It will be noted that the waste gas off-takes are entirely separate and independent 75 of the air and gas inlet and supply ports throughout the entire length of the said off-takes between the furnace chamber and the slag pocket. It will also be noted that it is only necessary to provide a single slag 80 pocket at each end of the furnace, the out-flow from each of these pockets being divided between the gas and air regenerators at that end of the furnace.

In the construction shown, each of the 85 valves 16, 17 may be protected by a refractory covering 17^a which can be retained in place by ribs or flanges 17^b formed on the metal body, as shown in Figures 5 and 7. The bent portion of the hollow valve stems 90 may be protected by a suitable covering, as indicated at 18^a, in Figure 5. The valve seat portions of the ports 10 and 12 and 13 and 15 may be protected by water-cooled 95 members 25.

If desired, the gas and air may be still more effectively mixed before being introduced into the furnace by a construction such as shown in Figures 8, 9 and 10. In this case, instead of there being a single gas 100 inlet port 7^c at each end of the furnace with a single air port arranged to discharge over and at the sides of the gas port, as above described, there is provided an alternating arrangement of gas ports 26 and air ports 105 27 placed side by side, each gas port 26 having an uptake 28 communicating with the main gas inlet port 29; and each air inlet port 27 having a connection with an uptake 30 from the main air inlet port 31. 110 The latter is also formed with a portion 32 which extends over the series of ports 26 and 27, thereby giving an additional supply of air at the discharge ends of said ports. By this construction a very thorough and 115 effective mixing of the air and gas may be had at the point of combustion and before discharge into the furnace chamber.

The advantages of my invention will be 120 apparent to those familiar with open hearth furnaces, since it provides a construction which results in a more effective operation of the furnace due to better and more complete combustion. The air and gas inlet ports being separate and independent from the offtake ports are prevented from being clogged or filled by waste products of combustion, and the life of the port walls is also greatly extended. Inasmuch as none of the waste gases pass out through the gas 125 130

and air ports, the walls of these ports can be made much thinner, and the construction can be so designed as to provide for much greater efficiency of the furnace. That is to say, these ports can be designed and constructed wholly from the standpoint of combustion efficiency. The invention also obviates the necessity of more than one slag pocket at each end of the furnace and permits of a very simple port arrangement as well as the use of a simple reversing valve arrangement.

It will readily be understood that the details of my invention may be varied widely within the spirit and scope of the appended claims.

I claim:

1. An open-hearth furnace having gas and air inlet ports at each end, separate offtake ports extending above said inlet ports, and gas and air-reversing chambers into which the inlet ports open at each end of the furnace, said reversing chambers having lateral and upper walls which separate said chambers from the said offtake ports, substantially as described.

2. An open hearth furnace having air and gas ports, and offtake ports which are separate and independent of the air and gas ports throughout their entire length from the furnace chamber to regenerators, substantially as described.

3. An open hearth furnace having a plurality of gas and air ports arranged in alternating relation at each end of the furnace, an arch over the said ports, and a secondary air supply port extending over said arch, substantially as described.

4. An open hearth furnace having a plurality of gas and air ports arranged in alternating relation at each end of the furnace, an arch for said ports, and an offtake above said arch, substantially as described.

5. An open hearth furnace having a plurality of gas and air discharge ports at each end of the furnace, an arch over each set of said ports, an offtake above the arch, and gas and air supply ports which are independent of the offtakes, substantially as described.

6. An open hearth furnace having gas and air ports at each end, a regenerator connected to each port, an offtake port at each end which is separate from the gas and air ports, a slag pocket at each end connected to the offtake port at that end, and valve means for passing the air and gas from their respective regenerators directly to the gas and air ports independently of the slag pocket, and for passing the waste gases from the uptakes through the slag pockets, and thence to the regenerators, substantially as described.

7. An open hearth furnace having at

each end a single slag pocket, an offtake leading from the furnace chamber to said pocket, two valve chambers adjacent each of said pockets, an offtake port directly connecting each valve chamber with the adjacent pocket, a gas supply port extending directly from a regenerator to and through one of said valve chambers, an air supply port extending directly from a regenerator to and through the other of said chambers, and valve means in said chambers for controlling said ports, substantially as described.

8. An open hearth furnace having at each end a single slag pocket, an offtake leading from the furnace chamber to said pocket, two valve chambers adjacent each of said pockets, a port connecting each valve chamber with the adjacent pocket, a gas supply port extending through one of said valve chambers, an air supply port extending through the other of said chambers, and valve means in said chambers for controlling said ports, together with regenerators directly connected to the valve chambers, substantially as described.

9. An open hearth furnace having a single slag pocket at each end, an offtake leading from the furnace chamber to each of said pockets, two valve chambers adjacent to each of said pockets, a port connecting each valve chamber with the pocket, a gas supply port extending through one of said valve chambers, an air supply port extending through the other of said valve chambers, and a pair of reversing valves at each end of the furnace, each of said valves being movable above a vertical axis from a position to close the port leading from the slag pocket to its valve chamber to a position to close the port leading from said valve chamber to the adjacent supply port, and vice versa, substantially as described.

10. An open hearth furnace having a single slag pocket at each end, an offtake leading from the furnace chamber to each of said pockets, two valve chambers adjacent to each of said pockets, a port connecting each valve chamber with the pocket, a gas supply port extending through one of said valve chambers, an air supply port extending through the other of said valve chambers, and a pair of reversing valves at each end of the furnace, each of said valves being rotatable about a vertical axis from a seating position over one port to a seating position over an adjacent port, substantially as described.

11. An open hearth furnace having a single slag pocket at each end, an offtake leading from the furnace chamber to each of said pockets, two valve chambers adjacent to each of said pockets, a port connecting each valve chamber with the pocket, a gas supply port extending through one of

- said valve chambers, an air supply port extending through the other of said valve chambers, and a pair of reversing valves at each end of the furnace, each of said valves being rotatable from a seating position over one port to a seating position over an adjacent port, and also having means whereby it may be moved vertically to seat and unseat it, substantially as described.
- 10 12. An open hearth furnace having two adjacent ports; a valve having a bent stem and rotatable to move the valve from one of said ports to the other, and means for
- rotating said valve, substantially as described.
13. An open hearth furnace having two adjacent ports, a valve having a bent stem and rotatable to move the valve from one of said ports to the other, and means for rotating said valve, together with other means for effecting a vertical movement of the said valve, substantially as described.

In testimony whereof, I have hereunto set my hand.

LUTHER L. KNOX.
